UNITED STATES PATENT OFFICE

2,536,622

BRACELET FOR WRIST WATCHES

Carl Egon Askholt, Copenhagen, Denmark, assignor of one-half to V. Siefert, Ikast, Denmark

Application October 14, 1948, Serial No. 54,379
In Denmark October 17, 1947

2 Claims. (CL 224—4)

1

The invention relates to bracelets for wrist-watches comprising substantially a pair of semi-circular strips of metal which are each hingedly connected with the wrist-watch by means of a hook and the free ends of which are adapted to be connected with each other by means of a locking-device. Each of the said semi-circular strips of metal may in accordance with the invention be formed with beaded edges which act to stiffen the strips and to retain strips of leather or other material for decorative purposes.

Furthermore, the said hook may be provided with a clamp comprising a tubular member of rectangular section into which one end of the semi-circular strip can be introduced, the strip being provided with a punched-out rectangular flap which after having been put through the rectangular tube of the clamp is bent through an angle of 180° in such a manner that the bent flap comes to lie on the inside of the bracelet so as to retain the strip at the clamp.

Finally, the invention resides in a special form of the locking device which will be more explicitly described hereinafter.

An embodiment on the watch bracelet in accordance with the invention is illustrated in the drawing in which

Figure 1 shows the bracelet without the watch, Figure 2 is a development of the outer side of one of the semi-circular metal-strips,

Figures 3 and 4 are a plan-view and a side-view respectively of the latch of the locking device,

Figure 5 is a development of the outer side of the other semi-circular metal-strips,

Figure 6 shows a blank for the production of a clamp for connecting the semi-circular strips with either strap of the watch,

Figures 7 and 8 are a side-view and plan-view respectively of the completed clamp,

Figure 9 is an inside view of the metal-strip shown in Figure 5 and provided with a clamp and

Figure 10 is a section taken along the line X—X in Figure 1.

As shown in Figure 1 the bracelet comprises a pair of semi-circular metal-strips 11 and 12 which are each connected with a clamp 13 having a hook 14, which is adapted to engage a strap on the watch in the manner known from most wrist-watch-bracelets. The metal-strips 11 and 12 are adjoined at 15 where they are connected with each other by means of a locking device hidden in one of the strips, the latch of which device has a projection 16 by means of which the latch can be displaced when the bracelet is to be put on or removed.

The metal-strip 12 which is shown partly de-

veloped in Figure 2 is formed with beaded edges 17, see Figure 10. At one end of the strip 12 the beaded edges 17 are so broad as to make contact along the line 18 so that this end of the strip 12 presents the form of a rectangular tube. Furthermore the tube is partly closed at its ends by means of a pair of flaps 19 flanged from the strip 12.

The latch 20 shown in Figures 3 and 4 is arranged inside this tube. The latch is at its front end formed with a cross-pin 21 behind which are recesses 22, each containing a flat coiled spring 23, Figure 2. The spring engages with its front end the flap 19 and with its rear end the latch 20 so as to normally hold the latch 20 in the position indicated in Figure 2. The latch can be pushed forward by placing the finger of the hand upon the projection 16 of the latch whereby the springs 23 are compressed.

A pair of slots 24 are punched out at the opposite end of the strip 12 so as to define a rectangular flap or tab 25, the purpose of which will be explained hereinafter.

The metal-strip 11 shown in Figure 5 is at one end formed with similar slots 24 so as to equally present a rectangular flap 25. At the opposite end of the strip the two flaps 17 are so broad as to similarly make contact along a line 26 corresponding to the line 18 of Figure 2. In this manner a rectangular tube is formed at the end of the strip 11, and this tube is like in Figure 2 partly closed by a pair of flaps 19' flanged from the strip 11. The strip 11 is formed with a punched-out aperture 27 comprising a pair of opposed notches 28. The aperture 27 and the notches 28 are of such size and shape that the latch 20 can be introduced therethrough into the strip 11 upon which the cross-pin 21 of the latch will engage the flaps 19' under the action of the springs 23. The locking device can now only be released if the projection 16 is manually displaced so much that the cross-pin 21 of the latch comes into register with the notches 28 and the latch can then be laterally disengaged from the strip 11.

The aforesaid clamp 13 with the hook 14 is made by folding the blank shown in Figure 6. The flap 29 is rolled to form the hook 14 and the two clamps 13 are bent towards each other as shown in Figure 8 so that this part of the clamp is constituted by a rectangular tube. The dimensions of this tube are such that one end of the metal-strips 11 and 12 can be introduced into the clamp which surrounds the end of the strip without clearance. The end of the flap 25 is now bent as shown in Figure 9 and the strip

and the clamp are thus firmly connected with each other.

The semi-circular strips 11 and 12 are covered on their outer faces by means of a strap 31 of leather, plastic or other material which is retained by the flanges 17 surrounding the edges of the strap. If the strap 31 is made of transparent material the face of the metal-strips covered by the strap may be decorated.

The length of the strips 11 and 12 are adapted to the circumference of the wrist of the person who shall wear the watch-bracelet, the parts of the strips situated outside the slots 24 being curtailed. Bending of the flap 25 may be effected at any place thereof, after the clamp 13 has been positioned upon the strip.

The strips 11 and 12 are preferably made of thin, mild sheet-metal and the clamps 13 of thin hard-sheet metal.

I claim:

1. A wrist-watch bracelet including two substantially semi-circular and serially connected metal strips adapted to partly surround the wrist and having the two opposite side edges thereof bent over to form beads; an end tab extending from one end of each strip with a pair of parallel open slots located at the sides of each end tab; a pair of short tubes terminating at an outer end of each in a hook adapted for connection to an end of a watch, the interior diameter of said tubes corresponding to the height and thickness of said semi-circular metal strips and the latter extending individually with their end tabs into said tubes; and retaining members formed by said tabs being bent substantially 180° about the outer ends of said tubes which carry said hooks and disposed opposite to the latter for retaining said tubes with their hooks assembled upon said semi-circular metal strips.

2. A wrist-watch bracelet including two substantially semi-circular and serially connected metal strips adapted to partly surround the wrist and having the two opposite side edges thereof bent over to form beads upon the exterior convex sides of the strips; an end tab extending from one end of each strip with a pair of parallel open slots located at the sides of each end tab; a pair of short tubes terminating at an outer end of each in a hook adapted for connection to an end of a watch, the interior diameter of said tubes corresponding to the height and thickness of said semi-circular metal strips and the latter extending individually with their end tabs into said tubes; retaining members formed by said tabs being bent substantially 180° about the outer ends of said tubes which carry said hooks and disposed opposite to the latter for retaining said tubes with their hooks assembled upon said semi-circular metal strips; and a pair of projecting end portions upon the outer sides of the open slots at the end of each metal strip extending through the tube respectively associated with each metal strip in effective position to cooperate with, and form a closure for, the hook on the respectively adjacent tube involved.

CARL EGON ASKHOLT.
